UNITED STATES PATENT OFFICE.

BERT C. BERRY, OF LONG BEACH, CALIFORNIA, ASSIGNOR TO BERRY SHOCKER INCORPORATED, OF WILMINGTON, DELAWARE, A CORPORATION OF DELAWARE.

SHOCKER.

Application filed February 21, 1921. Serial No. 446,843.

This invention relates to shockers, and has for its object the provision of a simplified construction and one which will be positive and efficient in its action.

5 More specifically, it is the object of the invention to provide a shocker including a sheaf receiver adapted to form a shock and so arranged as to be rotated in order to upend the shock, without employing gears or 10 similar mechanism for causing such rotation.

A still further object of the invention is to provide a mechanism of this character having means for automatically exerting 15 pressure upon the sheaves in the receiver while the latter is being rotated to upend the shock.

It is a still further object of the invention to provide improved means for spreading 20 the base of the shock as it is upended from the sheaf receiver in order that the shock will be firmly placed in upright position upon the ground.

Further objects of the invention will be 25 readily understood from the following description of the accompanying drawings, in which—

Figure 1 is a front view of a shocker constructed in accordance with the invention 30 and showing the attachment of the same to a binder.

Fig. 2 is a plan view of the shocker with the inclined deck conveying the sheaves, partly broken away.

35 Fig. 3 is a side elevation of the shocker viewed from the side adjacent to the binder, with the elevating mechanism removed.

Figs. 4 and 5 are similar views from the 40 opposite side showing respectively the position of the sheaf receiver when first released to cause rotation of the same, and when subsequently rotated to the position where the shock is upended.

Fig. 6 is a detail side elevation of the 45 releasing means for the sheaf receiver.

Fig. 7 is a section on the line 7—7 of Fig. 6.

Fig. 8 is a detail perspective view showing 50 the construction of the elevating conveyor.

Fig. 9 is a detail perspective view of the actuating shaft for the pressure arm.

Fig. 10 is a plan detail of the feeding chute and associated mechanisms.

55 The improved shocker comprises a main frame shown as a U-shaped frame 1 sup-

ported by rear wheels 2 and front wheels 3. The shocker is connected to the side of a suitable binder, the right-hand side traction wheel of which is shown at 4 with the conveyor deck for the sheaves projecting laterally beyond the same in usual manner as shown at 5. The shocker is positioned laterally beyond the conveyor deck 5 and is suitably connected to the binder by a draft connection 6. The front wheel 3 at the left-hand side of the shocker is preferably provided with a non-swivelling mounting, while the other three wheels of the machine are arranged to swivel so that the shocker will readily follow alongside of the course of the binder.

The sheaf receiver is supported by a swinging frame including cross bar 7 at the front of the main shocker frame and having rearwardly extending arms 8 adjacent the respective sides of the main shocker frame swingably connected to bar 7 as by pivot bolts 9. The arms 8 are normally held in upwardly swung position through suitable latching mechanism upon the rear swinging 75 ends of the same, engaging supports 10 depending from the side bars of main frame 1.

The sheaf receiver is rotatably mounted 80 between arms 8 as by means of stub axles 11 projecting inwardly from the swinging ends 85 of the arms. The sheaf receiver comprises arcuate tread members 12 forming the major portions of circles with their ends connected by straight sections 13 which give a flattened configuration to each of the tread members 90 on one side. These tread members are provided with upper cross rails 14 and with cross braces 15 depending therefrom to the bars 13 of the tread members. The sheaf receiving pan 16 is supported from the respective cross rails 14, and the sheaf receiver, as thus constructed, is journaled upon stub shafts 11 by receiving the same through 95 bearings 17 provided in braces 15 as shown in Fig. 3. The axis of the sheaf receiver 100 is eccentric with relation to the arcuate tread members 12, so that the forward and lower portions of the tread members when in normal position are closer to the axis of the sheaf receiver than the upper and rear portions thereof and when in this position the flat sections occupy a position above and at a slight angle with the ground.

The sheaf receiving pan is open at the top 110 and increases gradually in width from its

rear end to its forward end and is downwardly inclined. It includes a central depression 18 with the sides of the pan curving laterally therefrom and then curved upwardly and slightly reverse, as shown at 19, to the upper edges of the pan. By this arrangement when the sheaves are deposited longitudinally within the pan with the butt ends forward, and above the center thereof, 10 the first sheaf will be positively correctly positioned within depression 18, so that the following sheaves will be built up thereon to form a usual frusto-conical shock, having the base thereof at the enlarged forward end of the pan.

After the sheaves have been deposited in the receiver pan, and when the latter is rotated in order to upend the shock, pressure is exerted upon the upper side of the 20 sheaves within the pan so as to press the same into the form of a shock and retain the shock in position until the rotation of the sheaf receiver has upended it from the forward end of the pan on to the ground. 25 For this purpose a cam 20 is fixedly mounted on one of the bearings 17 so as to extend above the sheaf receiving pan when the latter is in normal position, and a shaft 21 is journaled upon one of the side rails 14, so as to project transversely inwardly over the 30 open upper side of the sheaf receiving pan. A crank end 22 extends rearwardly from the inner end of the shaft 21 and parallel to the upper edge of the pan so as to overlie one side thereof. The spring 23 upon the shaft 21 tends to swing the rear end of the crank 22 downwardly, and a lug 24 projecting from the shaft 21 and resting upon the cam 20 causes the downward swing of the 35 crank 22 to be restricted by the cam against the tension of the spring.

A sleeve 25 is journaled upon the crank 22 and is provided at its rear end with a laterally projecting pressure arm 26. The 40 sleeve is acted upon by a coil spring 27 which tends to elevate the pressure arm to an upright position, in which it will not obstruct the depositing of the sheaves within the pan, and this action of the spring is controlled by means of a rearwardly projecting tail piece 28 which engages the edge of the receiving pan. When the crank end 22 is swung downwardly, the tail piece will be 45 swept down in contact with the inner face of the pan, and the space between the sleeve and the pan being restricted the tail piece will be trailed behind the sleeve, thereby imparting rotation to the sleeve and causing the pressure arm 26 to be swung downwardly 50 against the sheaves within the pan. The downward or inner swing of the crank end 22 will be occasioned by the tension of the spring 23 under the control of the cam 20 which acts upon the lug 24. This rocking 55 of the sleeve 25 against spring tension, and

the resultant down swing of the pressure arm 26 across the pan, take place in sequence, so that as the pan is being tilted to deposit the shock upon the ground the pressure arm will be moved downwardly and rearwardly with respect to the main frame of the machine, thereby exerting a downward and rearward pressure against the body of the shock as the same is being butted upon the ground. The rearward component 70 of movement of the arm 26 at the time of delivery of the shock is substantially equal to the forward advance of the machine as a whole, so that the shock will be steadied at the instant it strikes the ground and its acquired momentum will be resisted in the manner stated, so as to overcome the tendency of the shock to topple forward during the return movement of the pan over the top of the shock.

The mechanism for normally retaining arms 8 in their upwardly swung position includes notches 30 provided in uprights 10 and latch members 31 pivoted to arms 8, and provided with rollers 31^a adapted to engage said notches to prevent downward swing of said arms or to be released therefrom, so that the arms and the sheaf receiver carried thereby will be lowered by gravity. The latches 31 are operated by connecting rods 32 extending to the front of the machine and preferably adjustably connected by means of nuts 33 to arms 34 depending from a rotatable cross rod 35. This rod is extended beyond the side of the machine 100 and is provided with a suitable operating connection 36 whereby it may be oscillated by the operator. The latching members are normally held in engaging position by means of springs 37 connected at their respective ends to arms 8 and to the arms 34, so as to yieldably move connecting rods 32 in a direction to cause engagement of the latch mechanism. It will be understood that when the operator swings rod 35 in the 110 opposite direction, that the latch mechanism is released so that the arms 8 and the sheaf receiver carried thereby are swung downwardly.

When the sheaf receiver is thus lowered, the forward lower ends of tread members 12 engage the ground and the continued forward movement of the shocker will cause the sheaf receiver to be rotated upon its axis provided by stub shafts 11 as the tread members continue to engage the ground.

The position of the mechanism, when the sheaf receiver is first released so as to drop to the ground, is shown in Fig. 4, and the position of the sheaf receiver, when it has been rotated so as to upend the sheaf receiver and thereby release the shock therefrom, is shown in Fig. 5. It will be noted that as the sheaf receiver swings from the position shown in Fig. 4 to the position 130

shown in Fig. 5, that the lug 24 moving along cam surface 20, will permit gradually increasing downward swing of the rear end of crank 22, and as a consequence the pressure arm 26 will exert a gradually increasing pressure against the shock within the receiver pan.

When the sheaf receiver reaches the point in its rotation where the shock will be 10 ended, as shown in Fig. 5, the pressure arm 26 is arranged to exert a final increased pressure against the shock as it is placed upon the ground in order to firmly form the same. For this purpose, shaft 21 is provided with 15 an arm 40 projecting laterally therefrom and adapted to engage lugs 41 depending from one of arms 8. The rotation of the sheaf receiver will thus cause shaft 21 to be further rotated by the abutment of arm 20 40 against lugs 41, and crank 22 will thereby be given a final increment of compressive movement, which with the pan in tilted position will be in a rearward direction as regards the line of advance of the machine, 25 thereby forcing the pressure arm 26 more firmly against the butted shock to restrain its tendency to topple over. When the arm 40 passes beyond the lugs 41, the lug 24 will already have passed under and become disengaged from the cam 20, and further rotation of the shaft will then be prevented by the contact of the lug 24 against a stop 24^a beneath the same, as shown in Fig. 9. As the pressure of the rod 26 is released by 30 the discharge of the shock and the concurrent advance of the machine, the continued rotation of the sheaf receiver over the top of the deposited shock to its normal or receiving position will cause the lug 24 to engage the rear or under portion of the cam 20, which is so configured as to swing the crank 22 upwardly against the tension of the spring 23, and thereby permit the arm 26 to swing upwardly under the influence of 35 the spring 27 as the tail piece 28 slides over the edge of the pan. The arm 26 thus moves out of the way of the sheaves to be subsequently deposited in the receiving pan.

It will also be noted that the eccentric configuration of the tread members causes the bearings for the pan to be lifted to their highest degree at the time when the pan is in overturned position and somersaulting forward over the top of the deposited shock, 40 and this arrangement affords the necessary clearance between the shock and the pan to prevent a toppling over of the butted shock by the contact of the pan on its return movement. The arrangement is also such as to cause the arms 8 to be swung upwardly by the acquired momentum of the pan as it returns to normal position, so that when the sheaf receiver has completed its rotation and is again in position to receive 45 sheaves, the arm 8 will be fully raised and

again held in such position by the latch mechanism. A stop 42 depends from the superstructure 43 of the shocker frame in alignment with one of the tread members 12, so that as the sheaf receiver completes its 70 rotation the stop will engage the tread member to prevent further rotation until the sheaf receiver is again lowered by operation of the latch mechanism, the relation of these parts being such that the lowering 75 of the sheaf receiver brings the axis of the pan sufficiently far forward to permit clearance of the stops when the pan is rotated.

The means for feeding the sheaves to the receiving pan lengthwise of the latter, includes a downwardly inclined chute 44 carried by the superstructure 43 above the rotating sheaf receiver and extending from the side of the machine, which is adjacent the binder, to a point over the center of the receiving pan.

At the side of the mechanism toward the binder, an elevating conveyor is suitably positioned to engage the sheaves as they are discharged from the deck 5 of the binder 80 and elevate the same so that they will drop on to the chute 44. This elevating conveyor comprises upper and lower sprockets 45-46 suitably mounted at the side of the shocker 85 and having an endless chain conveyor running over the same. The upper sprocket is preferably a drive sprocket and may be actuated by a bevel gear 48 meshing with a bevel gear 49 upon the sprocket and rotated by a sprocket wheel 50 having a chain 51 90 running over the same. This chain is preferably driven by a sprocket wheel 52 mounted upon the axle of the non-swivelling left-hand front wheel of the shocker.

The conveyor preferably includes chains 105 53 at the respective sides of the same and running in channel members 54. Pivotaly mounted rods 55 connect the respective chains and are provided with laterally projecting tines 56 which are adapted to be 110 swung outwardly so as to engage beneath a sheaf and elevate the same along the conveyor. The rods 55 are provided with laterally projecting lugs 57 at right angles to tines 56, and so positioned as to abut against channel member 54 during the upward flight of the conveyor, and thereby retain rods 55 115 against rotation and tines 56 in outwardly swung position for supporting the sheaves. As the conveyor passes over the upper sprocket, the sheaves are dropped into chute 44 and will roll down the same to a position above the center of the receiving pan and lengthwise thereof. In order to positively disengage the tines 56 from the sheaves as the latter move into chute 44, a projection 120 59 is preferably formed at the side of the conveyor in such position as to engage tines 56, so as to swing the rods and thereby move the tines away from the sheaves. This is 125 130

permitted by the emergence of the lugs 57 from the channels best shown in Fig. 8 before the tines encounter the projection 59.

As previously stated, the chute 44 terminates above the center of the receiving pan, and a hopper for the passage of the sheaves is formed between the end of the chute, and tines 60 spaced therefrom and mounted upon a pivotally supported cross rod 61. The tines 60 are normally swung upwardly to the position shown in Fig. 1 so as to engage the sheaves as they pass beyond the end of chute 44, and when in such position the dropping of a sheaf to the receiving pan is prevented. 10 15 The tines engaging a sheaf will also correctly position the same with relation to the sheaf receiving pan, so that the sheaf is exactly above the central depression of the pan and parallel thereto. When the receiving pan is 20 in its normal position to receive the sheaves, the weight of a sheaf against tines 60 will rotate rod 61 against the tension of yieldably retaining means in order to permit the 25 passage of the sheaf, which will thus be dropped horizontally into the receiving pan and exactly parallel to its length.

The yieldable retaining means preferably consist of an arm 62 projecting upwardly from pivot rod 61 and connected by a spring 30 35 40 45 50 55 60 65 70 75 80 85 90 95 100 105 110 115 120 125 130 135 time the shock is deposited, and finally of supporting the shock momentarily as the pan is rotated over the top of the shock on its return movement. These several functions are attained by reason of the combined movements which are imparted to the pressure arm, first by means of the axial rotation of the sleeve upon which the pressure arm is mounted, and second by reason of the 10 rotation of the crank section in a direction which is downward and rearward with respect to the ground surface.

The provision of an adjustable tread permits the movements of the pan to be regulated with due regard to the height of the grain and ground conditions, so that the pan may always be adjusted to a sufficient height to clear the top of the deposited shock. The formation of the pan with the central channel or depression insures the building up of a symmetrical shock, since the first sheaf, being centrally deposited, assists in causing the remaining sheaves to take positions in the pan in parallel relation to one another.

25 Various changes may be made without departing from the spirit of the invention as claimed.

What is claimed is:

1. In a shocker, the combination of a main frame, supporting frame members pivoted forwardly to the main frame, a pan trunnioned between the supporting frame members, means for holding the supporting frame members in elevated position and 30 adapted to permit lowering thereof, an arcuate tread member adapted to contact the ground when the supporting frame members are lowered for imparting rotation to the pan, means for elevating and delivering sheaves of grain to the pan, a gate for arresting the delivery of sheaves during the rotation of the pan, and trip mechanism adapted to be engaged by the tread member when elevated to hold the gate in open relation and adapted to be actuated to close the gate when the tread member is lowered and in ground contact, substantially as described.

2. In a shocker, the combination of a frame, a pan rotatably mounted with respect thereto, means for rotating the pan, a pressure arm extending transversely of the pan, means for swinging the pressure arm to bring its inner end toward the base of the pan, and means for moving the pressure arm rearwardly during the butting operation at a speed commensurate with the advance of the shocker to maintain temporary contact with the shocker when butted, substantially as described.

3. In a shocker, the combination of a frame, a pan rotatably mounted with respect thereto, means for rotating the pan, a pressure arm extending transversely of the pan, means for swinging the pressure arm to bring its inner end toward the base of the

pan, and means for moving the pressure arm rearwardly during the butting operation at a speed commensurate with the advance of the shocker to maintain temporary contact with the shocker when butted, said means 70 for imparting movements to the pressure arm being actuated by rotation of the pan, substantially as described.

4. In a shocker, the combination of a frame, a pan rotatably mounted with respect thereto, means for rotating the pan, a pressure arm extending transversely of the pan, means for swinging the pressure arm to bring its inner end toward the base of the pan, and means for moving the pressure arm rearwardly during the butting operation at a speed commensurate with the advance of the shocker to maintain temporary contact with the shocker when butted, said means 75 for imparting movements to the pressure arm being actuated by rotation of the pan, substantially as described.

5. In a shocker, the combination of a frame, a pan rotatably mounted upon the frame and vertically adjustable thereto, a tread member fixedly associated with the pan, an adjustable member on the tread for regulating the degree of elevation imparted 80 to the pan during its period of rotation, substantially as described.

6. In a shocker, the combination of a main frame provided with supporting ground wheels, a pan, supporting members upon which the pan is rotatably mounted, said supporting members being mounted for vertical movement with respect to the main frame, means for normally holding said supporting members in elevated position and adapted to permit the lowering of said supporting members together with the pan, a tread member fixedly associated with the pan and adapted to contact the ground when the supporting members are lowered, and an adjustable tread adapted to regulate the degree of the lifting effect of the tread member, substantially as described.

7. In a shocker, the combination of a main frame provided with supporting ground wheels, a pan, supporting members upon which the pan is rotatably mounted, said supporting members being mounted for vertical movement with respect to the main frame, means for normally holding said supporting members in elevated position and adapted to permit the lowering of said supporting members together with the pan, a tread member fixedly associated with the pan and adapted to contact the ground when the supporting members are lowered, and an adjustable tread adapted to regulate the degree of the lifting effect of the tread member, said adjustable tread being pivoted at 110 one end to the tread member and being 115

provided with an adjustable connection at its opposite end, substantially as described.

8. In a shocker, the combination of a main frame, a pan rotatably mounted with respect to the main frame, said pan being open at its end and on its normally upper side, a pressure arm extending from one side of the pan toward the longitudinal center of the pan, a shaft extending transversely through one side of the pan near the rim thereof and provided on its end with an angularly disposed crank portion upon which the pressure arm is journaled, means for swinging the pressure arm to move its acting end toward the base of the pan, and means for rocking the shaft with its crank to move the pressure arm during the butting movement of the pan to cause the pressure arm to maintain temporary contact with the shocker while being butted, substantially as described.

9. In a shocker, the combination of a main frame, a pan rotatably mounted with respect to the main frame, said pan being open at its end and on its normally upper side, a pressure arm extending from one side of the pan toward the longitudinal center of the pan, a shaft extending transversely through one side of the pan near the rim thereof and provided on its end with an angularly disposed crank portion upon which the pressure arm is journaled, means for swinging the pressure arm to move its acting end toward the base of the pan, and means for rocking the shaft with its crank

to move the pressure arm during butting movement of the pan to cause the pressure arm to maintain temporary contact with the shocker while being butted, said means including a non-rotatable cam and means associated with the shaft and co-acting with the cam, substantially as described. 40

10. In a shocker, the combination of a frame, a pan rotatably mounted with respect thereto, said pan being trough-shaped with rounded side walls, and tapering from front to rear and open at its ends and on its normally upper side, and provided in its base with a longitudinally extending centrally disposed channel of smaller radius of curvature than the radius of the proximate lateral portions of the pan, and means for rotating the pan, substantially as described. 45

11. In a shocker, the combination of a frame, a pan rotatably mounted with respect thereto, said pan being trough-shaped with rounded side walls, and tapering from front to rear and open at its ends and on its normally upper side, and provided in its base with a longitudinally extending centrally disposed channel of smaller radius of curvature than the radius of the proximate lateral portions of the pan, means for rotating the pan, and means for discharging bundles from a point above the pan toward the channel in the center of the base of the pan, substantially as described. 50

In testimony whereof I have signed my name to this specification.

BERT C. BERRY.
